UNITED STATES PATENT OFFICE

WILLIAM CAMERON, OF CHICAGO, ILLINOIS, ASSIGNOR TO CAMERON CAN MACHINERY CO., OF CHICAGO, ILLINOIS, A CORPORATION OF ILLINOIS

AUTOMATIC STOP MECHANISM

Application filed February 18, 1928. Serial No. 255,229.

This invention relates in general to metal working machines and more particularly to a mechanism for automatically stopping such a machine when more than one or an excessively thick blank is fed thereto.

I am aware that machines of the above type have been in use employing mechanism for automatically stopping a press or other machine in the event one of the sheets or blanks being fed is warped or bent. However such machines are incapable of taking care of a contingency wherein more than one blank is being fed at a time because of the relative thinness of the blanks and the resultant slight movement given to the stop mechanism by the additional blank or blanks.

The primary object of this invention is therefore to provide an automatic stop mechanism for use in connection with a machine of the above type which prevents the feeding of more than one blank at a time and other false operations or defective conditions which would in the machines used heretofore, result in an ineffective initial movement delivered to the stop mechanism by reason of the slight abnormality in the thickness of the material being fed.

Other and further objects of this invention will become apparent as the same becomes better understood from an examination of the specification and claims in connection with the accompanying drawings wherein

Fig. 1 is a side elevation of an automatic die press of the type illustrated and described in connection with my copending application Serial No. 14,624 filed March 11, 1925 and also illustrated in connection with my prior Patent No. 1,477,240 of December 11, 1923 showing a preferred form of the invention applied thereto.

Fig. 2 is an enlarged cross sectional elevation showing the feed channel and parts of the automatic stop mechanism;

Fig. 3 is a fragmentary enlarged detail section taken at the line 3—3 of Fig. 2;

Fig. 4 is a top plan view of the portion of the device shown in Fig. 2;

Fig. 5 is a fragmentary side elevation partly in section and partly broken away of

a blank feeding mechanism of a type adapted to be used for feeding blanks to various forms of metal working machines, for instance, a can body making machine.

Fig. 6 is a fragmentary plan view of the mechanism shown in Fig. 5;

Fig. 7 is a fragmentary vertical transverse sectional view of the mechanism shown in Figs. 5 and 6 with parts in elevation;

Fig. 8 is a fragmentary detail vertical longitudinal section with parts in elevation showing the movement of the stop mechanism imparted thereto when more than one sheet is fed.

Referring to the drawings more particularly;

The machine illustrated in Figs. 1 to 4 inclusive comprises generally a frame 8 provided near its top with suitable bearings 9 in which the main power shaft 11 is journaled. The shaft 11 is suitably driven and provided with a fly wheel or a belt pulley 12 and a central crank between the spaced bearings 9 by means of which the usual cross head 13 is reciprocated in the guideway of the machine frame to reciprocate the upper die to cooperate with the stationary lower die mounted upon the bed of the machine. The blanks of tin or other material to be operated upon indicated at 14 are disposed in a pile in the inclined magazine or support 15 from which they are lifted in succession by a series of suction cups (not shown) into alignment with the feed channel or slot whereupon they are moved laterally edgewise into this channel by suitable transferring devices 16. The operation of the afore-mentioned parts will be clearly understood from my prior Patent No. 1,277,342 granted August 27, 1918 and my afore-mentioned copending application.

The magazine 15 is integrally mounted on, or connected to a frame part 20 which includes a guideway and carries a suitable feeding device for advancing the blank or sheet after it has been fed into position in the channel or groove. This feeding device consists of a feed bar 17 having a plurality of pivoted feed dogs 18 and capable of being reciprocated by a cross head 19 which is actuated from the power shaft of the machine by means

of connections generally designated as 21. The frame part 20 includes a bottom or table plate 22 having a channel 23 in the lower portion thereof for receiving attaching bolts 24 of a bracket 25 which is mounted on the plate in fixed position but adapted to be adjusted should occasion require by reason of said bolts. The channel 23 is of T-shaped cross section whereby, when the bolts are tightened by means of nuts on their respective outer ends the bracket is firmly held in position but when the nuts are loosened lateral displacement of the bracket is permitted. The bracket 25 is provided with a pair of projecting pivot arms 26 between which a lever 27 is pivoted intermediately of its ends as at 28.

The upper end of the lever 27 is split to provide jaws 29 between which an adjustable thumb screw 31 is threaded. This thumb screw can be fixed securely in position by tightening the jaws 29 by means of a screw 32 connecting them together. The thumb screw 31 is adjusted to engage a movable wall of the feed slot whereby it may transmit the movement of said wall to the lever 27 to stop the press as will be hereinafter explained.

The bracket 25 below the point where it engages the bottom plate or table 22 is provided with a circular hole for seating a spiral spring 33. The spring 33 engages in a recess 34 in the lower end of the lever 27 whereby it may normally urge said lower end outwardly.

The lower end of the bracket 25 is provided with a pair of arms 35 for supporting a bell crank lever 36. One end of the lever 36 is yieldably held against a ball portion 37 on the lower end of the lever 27 by means of a spring 38 connecting the other end of said bell crank lever and the bracket 25. The latter end of the bell crank lever 36 is provided with a hook portion 39 normally in engagement with a pawl 41 pivotally carried by the bracket 25.

By reference to Fig. 1 of the drawing hand lever 42 together with associated mechanism for starting and stopping the press is shown in dotted lines. The hand lever 42 is fixedly mounted on a shaft 43 and has an extension 44 pivotally connected with a link 45. The mechanism shown in dotted lines in the drawing whereby the handle 42 may stop the press is substantially the same as shown in my United States Letters Patent No. 1,477,240. On the shaft 43 at the opposite side thereof from the handle 42 is mounted a bell crank lever 46 the upper end of which is pivotally connected at the point 47 with one end of an adjustable connecting rod 48. The other end of the rod 48 is pivotally connected to the pawl 41 and the other end of the lever 46 is connected to a spring 49 attached to the frame whereby the shaft 43 may be actuated to stop the press when said pawl is released.

The movable wall 51 of the feed slot is

mounted above the feed bar 17 and is carried by shoulders 52 and 53. The shoulder 52 is formed on the frame part 20 above the table 22 and the shoulder 53 is formed on an oiling device 54 mounted on the opposite end of said frame. The oiling device 54 is of the type described in my afore-mentioned copending application. The wall 51 is provided at one end with a suitable handle 50 for removing the wall from its operative position when desired.

This removable wall 51 has a groove 55 extending longitudinally thereof on its under-face to allow sufficient clearance for the feed dogs 18 so that the latter may be oscillated to engage the rear edge of a blank in the feed channels whereby the dogs may feed the blank forward at each step a distance equal to the distance between two of the dogs.

The wall 51 is so positioned as to provide the feed slot 56 between said wall and the upper surface of the table 22 for the admission of a blank 14. The inner end of the screw 31 is adjusted to a position whereby outward movement of the plate or wall 51, 99 because of buckling or the like will cause actuation of the lever 27 which will in turn actuate the bell crank 36 to release the pawl 31 and automatically stop the press as previously explained. The afore-described parts, 95 and the operation thereof for automatically stopping the press in the event of a distortion of the plate 14 have been described in connection with my afore-said copending application.

It is desirable however to stop the press automatically not only in the event of an abnormality such as a distorted or buckled blank being fed but also in the event of two or more blanks being fed at the same time. 105 Because the blanks ordinarily used, particularly in the can making industry are relatively thin the presence of an extra blank in the slot 56 would not ordinarily cause the wall 51 to move sufficiently to stop the press unless at least one of the blanks were distorted or buckled.

In order that the press may be automatically stopped in the event of two blanks being fed, I provide in addition to the afore-described parts, upwardly directed extensions 57 on the arms 26 between the upper ends of which a link 58 is pivotally mounted. The link 58 is provided at its inner end with a semi-spherical projection 59 spaced from the lower wall of the feed slot 56 just sufficiently to accommodate a single blank between the wall and the member 59. A link 61 connects the inner end of the link 58 with the lever 36 so that swinging movement of the inner end downwardly, will cause the lever 36 to release the pawl 41 and automatically stop the press as has been explained.

In order to provide for a fine regulation and adjustment of the spacing of the mem- 130

ber 59 from the lower wall of the feed slot 56, the pivot pin 62 (Fig. 3) from which the link 58 is suspended is eccentrically formed between its bearings as indicated at 5 60. Angular adjustment of the pin will therefore regulate the spacing of the member 59 from the opposite wall of the feed slot. Adjustment of the pin may be accomplished by a wrench or tool shaped to fit the squared 10 head 63 of the pin which is locked in the desired position by clamping bolts 64 adapted to compress the split bearing within which the pin is mounted.

The member 59 is normally spaced away 15 from the opposite wall of the feed slot a distance only very slightly in excess of the thickness of a single blank being fed. Should two blanks instead of one be accidentally fed into the slot the entering edge 20 of the upper blank will strike against the member 59 and as it is shoved inwardly by the transferers the link 58 will be swung in a counterclockwise direction viewing Fig. 2 and thru the link 61 the lever 36 will be 25 rocked to release the pawl 41 and cause the press to be stopped.

In Figs. 5 to 8 inclusive there is shown a construction wherein this invention is applied to a blank feeding machine of the type 30 illustrated and described in connection with my prior Patent No. 1,283,659 of November 5, 1918. Referring to these figures it will be observed that the machine includes a frame portion 65. While the machine may 35 be of any type adapted to operate upon sheet metal blanks it is illustrated in these figures as a can body forming machine the frame of which is shaped to provide a slideway 66 upon which the blanks are fed to the body 40 forming mechanism (not shown). The blanks are fed from a magazine designated generally by reference character 67 along the slideway by means of reciprocating feed bars 68 provided with a plurality of feed dogs 69 45 pivotally and yieldably mounted upon the feed bar so that their rear ends engage with the successive sheets and feed them toward the operating mechanism in a step by step movement in a well known manner.

50 Mounted on the frame at the inner end of the guideway 66 is a switch box 71 from which projects a pivotally mounted arm 72. The arm 72 is arranged so that in its normal position it is 90° from the plane of the guideway 66. The outer and free end of the arm 72 is provided with a roller 73 which normally extends to the level of the guideway 66. On the frame above the roller 73 there is adjustably mounted a considerably larger roller 55 74 the periphery of which extends to within the thickness of a blank of the level of the guideway. The guideway 66 is provided with a depression 75 which extends on either side of the rollers 73 and 74 whereby when 60 more than one blank is being fed the blanks

may be forced downwardly by the roller 74 to bring the lowermost blank or blanks in contact with the roller 73 causing the arm 72 to be actuated about its pivot. The radius and position of the arm 72 is such as to give 70 the roller 73 when so contacted considerable linear movement in a circular path substantially in the plane of the advancing blanks and in the direction of movement thereof.

The mounting for the roller 74 is adjustable to permit the periphery thereof to be adjusted toward and away from the level of the guideway to accommodate different thicknesses of blanks which may be desired to be fed. The roller 74 is mounted on a pin 70 which like the pin 62 is eccentrically formed and angularly adjustable. It also may be locked in adjusted position by clamping bolts 80. Since the roller 73 is supported to move substantially in the direction of the guideway on being contacted by an abnormal number of blanks considerable movement is imparted to the stop mechanism. This permits the arm 72 to actuate a switch which is released when said arm is actuated. This 85 switch includes a double contact element or blade 76 carried by the arm 72 and adapted when the arm is in normal position to close contacts 77 in circuit with the driving motor 90 of the machine. A compression spring 78 yieldably holds the arm 72 in normal position. Thus when more than one blank is fed the arm 72 will be actuated to open the switch of the driving motor and automatically 95 stop the machine.

The operation of the afore-described embodiments of my invention will be clearly understood from the above description when taken in consideration with the disclosures in my prior patents.

100 It will be apparent that by supporting the member adapted to be contacted by the abnormal number of blanks in a manner whereby said member moves substantially in the direction of the moving blanks instead of 110 at right angles as heretofore, the stop mechanism has imparted thereto sufficient initial movement to permit its operation regardless of the relative thinness of the blanks.

I am aware that many changes may be made and many details of construction varied without departing from the principles of this invention and I therefore do not wish to be limited to the details shown or described.

115 I claim:

1. In a machine for operating upon blanks the combination of means for feeding blanks edgewise, a detector mounted to swing in an 125 arc about a pivot remote from the path of movement of said blanks, the detector being normally positioned so that a line intersecting said pivot and the point of the detector nearest the path of travel of the blanks will be per-

pendicular to said path of travel, and means rendered operable by swinging movement of said detector away from normal position under the influence of said advancing blank for stopping said machine.

5 2. In a machine for operating upon blanks the combination of means for feeding blanks edgewise in a predetermined path, pivotally mounted means normally positioned in proximity to said path and mounted so as to be immovable from normal position in a plane perpendicular to the path but movable substantially parallel with said path under the influence of advancing blanks, and means 10 operable by said movement for stopping the machine.

20 3. In a machine for operating upon blanks, the combination of means for feeding blanks edgewise, a feed-way including a fixed member along which the blanks are fed, a detector comprising a pivotally mounted member normally disposed a predetermined distance from said fixed member and immovable from normal position in a plane perpendicular to said fixed member, said detector being 25 adapted to swing bodily about said pivot away from normal position, and means rendered operable by said swinging movement under the influence of an advancing blank for 30 stopping the machine.

35 4. In a machine for operation upon blanks, the combination comprising means for moving a blank edgewise, a detector having a blank contacting extremity, said detector being pivoted at a point laterally removed from the path of travel of said blanks and extending substantially transversely of said path, said contacting extremity lying in the path of a surplus blank and displaceable thereby 40 substantially in the direction of blank travel, and means controlled by said movement of said contacting extremity for stopping the machine.

45 5. In blank feeding mechanism, the combination comprising means for feeding blanks edgewise, a detector having a blank contacting extremity supported to lie across the path of travel of a surplus blank and to be operatively engaged thereby but inoperative upon 50 normal blank feeding, means for movably mounting said detector and contacting extremity so that the latter will be bodily displaced by and carried with said surplus blank substantially in its direction of travel, and 55 machine controlling means actuated by the bodily movement of said contacting extremity under the travel of a surplus blank.

60 6. In a machine for operating upon blanks, the combination of means for advancing blanks along a predetermined path, a fixed member at one side of said path, a movable member at the opposite side of said path arranged to lie across the path of travel of a surplus blank and mounted to move bodily 65 in an arc to which said path is tangent, and

means rendered operable by the bodily displacement of said movable member under the influence of an advancing surplus blank for stopping the advance of said blank.

7. In a machine for operating upon blanks, the combination of means for advancing blanks along a predetermined path, a pivoted arm disposed substantially perpendicular with the plane of advancing blanks with its free end in position to be engaged and positively displaced by excessive blanks and to be moved along with said blanks, and means rendered operable by movement of said arm for stopping the operation of said advancing means.

70 75 80 In witness of the foregoing I affix my signature.

WILLIAM CAMERON.
